DRAFTING TEXTILE FIBERS

Wilfred J. Cabana, Woonsocket, R. I., assignor to
Uxbridge Worsted Company, Inc., Uxbridge,
Mass., a corporation of Massachusetts

Application December 10, 1946, Serial No. 715,329

24 Claims. (Cl. 19—131)

1

This invention relates to drawing textile fibers and pertains particularly to the worsted art.

The invention concerns generally the attenuation of strands of loose fibers, such as slivers and rovings and treatment thereof, to produce yarns, threads and the like, which are suitable for being made into textile fabrics.

The invention has among its objects the production of improved yarn, which has a better appearance, is stronger and has less "wild" fiber than heretofore obtainable, and in which the fibers are substantially parallel and give a soft, lofty effect.

It is also an object to produce any of a wide variety of blends of different fibers, differing not only as to length of fiber, weight, thickness and other physical characteristics, but also differing as to origin and whether natural or synthetic, or derived from animals or plants.

Furthermore, it is an object to provide arrangements for drawing such fibers rapidly, at relatively little expense, very nearly without breakage and substantially without stressing the fibers, or slivers, rovings, slubbings and the like, beyond their elastic limit.

Moreover, it is an object to produce yarns having the qualities of yarn produced by the so-called French or continental system of worsted production, while employing even fewer operations than involved in the so-called English or Bradford system, or other modified systems heretofore proposed for obtaining the French soft rovings.

A further object is to provide methods and apparatus for drawing fibers which are of general utility and not limited to the worsted art, and still another object is to provide ready adjustability for the most efficient processing of different fibers and blends of fibers.

Other and further objects, features and advantages of the invention will become apparent as the description proceeds.

In carrying out the invention while drafting strands of fibers, such as slivers, rovings and the like, fiber control is maintained continuously throughout the drafting area. To this end during each passage of the fibers, through successive processing units, the fibers of the incident strand are maintained under lateral pressure or thrust continuously throughout the length of the

2

drafting area, by pressure applying members located along the path of the strand to engage the traveling strand continually during its passage through the drafting area.

5 In accordance with the invention the fibers are maintained loose, and in substantially untwisted condition, throughout the worsted process until the fibers are spun in the final step of the process of fabricating yarn. This produces a lofty yarn, without sacrificing strength. The drafting of strands of fiber under continuous fiber control throughout the length of the drafting area enables the strands to be processed readily in un-twisted condition.

10 Heretofore, in the fabrication of worsted yarn, it has been the practice to take a batch of wool fibers from storage space containing a predetermined blend and to scour, card and comb them. The batch leaves the combing machine in the form of a sliver, which is free from lumps, bunches and foreign matter, and in which the fibers lie substantially parallel. The product of the combing machine according to the prior practice is given several gilling operations to produce material in the form known as "tops." The tops are given several passages through drawing frames, two or more passages being through gill boxes which are particularly designed to parallelize the fibers. This and other operations, including doublings, are to obtain a level end. All these operations are preliminary to the final spinning of the yarn.

15 Under one system of the prior art worsted process, tops are given two or more passages through gill boxes, and these passages are followed by several through drawing frames, such as finishers, reducers and rovers, which do not include gill boxes. In each of the latter drawing frames, the attenuated product strand of fibers is twisted, and wound on bobbins in the twisted condition. In each next succeeding passage, the twist is substantially removed during the drafting operation, it being necessary that the fibers be directed longitudinally of the strand during its attenuation.

20 The object of twisting the product strands of certain passages in the prior art practice, is to control their fibers during and between the various operations of the process. For a similar purpose, false twist is usually applied to the

product sliver of the passage through a gill box, the sliver in false twisted condition being packaged into a ball. The false twist is also removed in the next succeeding passage, whereby the strand is in an untwisted condition when it is being attenuated.

In accordance with the present invention, I avoid twisting the product strand of the given passage and removing twist in the drafting operation in the next succeeding passage. Among other advantages obtained in accordance with the present invention is the elimination of the loss of piece-up waste.

I have discovered that an improved worsted yarn can be made with fewer operations when fiber control is maintained continuously during each drafting operation. Beginning with the product sliver of the combing machine, instead of with tops as in the prior art practice, the strand is given a number of passages including doublings, for the desired blending to get a level end. The strand is gradually reduced in successive passages, or may be substantially reduced in one of the passages, the last passage under one practice of the process of the present invention, producing a roving which is ready for spinning. The passages which include doublings are preferably all through drafting frames which embody pin drafting machines. These machines are similar in their general principle of operation to gill boxes well-known to those skilled in the art. None of the passages which include doublings are through drawing frames like the finishers and reducers of the prior art, which twist the product strand. Accordingly there is no piece-up in carrying out the present invention.

The product sliver of each passage, even though it is in untwisted condition, does not lose fiber control after it leaves the drafting area. The fibers continue under control with normal handling of the strand in the manner hereinafter described up to the drafting operation of the next passage where means are again provided for positively maintaining fiber control. The really critical time when fiber control is likely to be lost is when the strand is being worked, attenuation of the strand constituting the principal working in the worsted process which is severe enough to cause the loss of fiber control.

A fabric woven of the loftier yarn produced in the practice of the present invention is fuller than Bradford yarn and equal in fullness to French yarn. The fabric is stronger, its component yarns being stronger than prior art yarns. As high as 15% greater strength has been observed in yarns of comparable fiber content and count, and yarns for comparable use in fabric, than has heretofore been obtainable in the customary worsted processes.

Under the prior art worsted process, the length of ratch is adjusted for control of fibers in the drafting area, the adjustment being in accordance with the length of fibers in the given batch. A short ratch is used for a batch of short fibers and the ratch is lengthened accordingly as the batch contains longer fibers, or a greater percentage of long fibers. In a batch of long fiber wool, for which a long ratch is used, there is a tendency to lose control of the shorter fibers, with a resultant tendency towards bunching, and also a loss of fibers in fly waste. In the case of a batch of short fiber wool, for which a short ratch is used, fibers which are longer than the length of the ratch are subjected to lacerating tension, which breaks them.

Therefore, under prior art practice, a blend of fibers is prepared with a predetermined degree of uniformity of fiber length, and the ratch is adjusted in accordance with the predominant length of fibers in the batch taken from a given blend. However, in a blend of fibers, either short or long, there will be some fibers which are longer than, and others which are shorter than, the desired or predominant length range or gradient. Grades of wool are, accordingly, selected for a blend to have a low percentage of fibers which are shorter and longer than the predominant length range.

In practicing the present invention, there is continuous fiber control throughout the length of the drafting area, there is no limitation of the range of fiber lengths that may be contained in the batch of fibers being processed. With means provided along the path of the strand in the drafting area to apply fiber controlling lateral thrust continuously, the shorter fibers of the batch are held under control. Not only is the ratch adjusted long enough to avoid lacerating back draft tension being applied to the longest fibers, but a soft control is employed. Gradually increasing lateral pressure is applied to the strand for gradually increasing resistance to movement thereof, so that there is no danger of breaking the longest fiber, and the shortest fibers are held parallel to the others and within the strand. The permissible diversity of fiber lengths, in carrying out the present invention, is so versatile that it is feasible, for example, to blend cotton and wool fibers, and to fabricate yarn of blended cotton and wool under the new worsted process of the invention, although cotton fibers are relatively short in comparison with wool fibers. It is also feasible to blend a wide variety of natural and synthetic fibers, different in length and in character of fiber.

When a blended yarn is desired under prior art practice, for example, when a yarn is to be fabricated of different types of fibers which, by way of illustration, might be wool and a decorative rayon fiber, the blending is usually begun in the doublings of tops. Packages of the various types of fiber, which have previously been prepared to have uniform fiber length in the different packages of different types of fibers, are fed as several ends in a passage through a gill box. The wool fibers are supplied in the form of tops, which are the product slivers of the combing machine, after they have been given two or more finish gilling operations. The finish gilling of tops is not unlike later passages of tops through gill boxes in continuance of the worsted process, and in fact constitute the first of several drafting passages of the prior art practice of fabricating worsted yarn.

The worsted process of the present invention preferably begins with the sliver product from the combing machine, and begins before the finish gilling operations which produce tops. For example, if a blended yarn is desired, slivers of the various types desired in the blend are fed to a pin drafting machine as the several ends of doublings, the wool slivers being fed from cans, in which they were received directly from the combing machine. Thus, blending of all the fibers which are being fabricated into the yarn is begun simultaneously with the blending of the several grades of wool fibers contained in the wool batch.

A better understanding of the invention will be afforded by the following detailed description

considered in conjunction with the accompanying drawing, in which:

Fig. 1 is a block diagram representing an illustrative combination of units to form a drafting system and diagrammatically indicating the method employed;

Fig. 2 is a schematic diagram in side elevation representing a pin-drafting machine which may be employed;

Fig. 3 is a fragmentary assembly drawing in 10 elevation of a frame for drafting and spinning the rovings;

Fig. 4 is a fragmentary side view of my apron type roving drafting head;

Fig. 4a is an enlarged fragmentary view of a 15 portion of the apparatus of Fig. 4;

Fig. 5 is a perspective view of the apparatus of Fig. 4;

Fig. 6 is a front elevation of the drafting head represented in Figs. 4 and 5;

Fig. 7 is a side elevation of the apparatus of Fig. 6;

Fig. 8 is a schematic diagram of the sliver condensing elements of the pin drafter shown in Fig. 2, the condensers being represented by the outlines cut by a horizontal plane;

Fig. 9 is a schematic diagram of the apparatus of Fig. 8, representing outlines cut by a series of vertical planes;

Fig. 10 is a diagram of sliver cross-sections at successive positions in the apparatus of Figs. 8 and 9 but drawn to an enlarged scale;

Fig. 11 is a side elevation of a portion of the apparatus shown in Fig. 7, with a modified bearing block for the free-running ratch roll, and the addition of a switch responsive to breakage of the strand being drafted for the purpose of interrupting the supply of strand to the draft control aprons;

Fig. 12 is a fragmentary view of the apparatus of Fig. 11 with certain portions thereof broken away to expose a section cut by the plane 12-12 indicated in Fig. 13, and showing the parts in a position assumed after a breakage in the strand has occurred; and

Fig. 13 is a fragmentary top view of the portion of the apparatus of Fig. 11, controlling the free-running ratch rolls.

Like reference characters are utilized throughout the drawing to designate like parts.

As indicated schematically in Fig. 1 of the drawing, the process of the present invention commences after the fiber has left the combing machine in the form of slivers. The sliver, combed in suitable apparatus of conventional type, is passed through a plurality of pin-drafting machines, for example, two to four such machines, then preferably passed through a cone rover, and finally through a drafting and spinning frame employing a novel type of drafting head forming a part of my invention. As will be described in greater detail hereinafter, the pinning of the pin-drafting machines is preferably made progressively finer. A number of ends are applied to each pin-drafting machine so as to obtain a desired number of doublings. Thus a plurality of slivers, for example six slivers, are fed to a pin-drafting machine 11 in which pins are relatively widely spaced in comparison with subsequent pin-drafting machines. The product of the relatively coarsely pinned drafting machine 11 is supplied to a can and such a product with further doublings, for example six ends up, is supplied to a second pin-drafter 12. The product of the second pin drafter 12 is, in turn,

supplied to the third pin drafter 13, for example with five ends up; and the product of the third pin drafter 13 is, in turn, supplied to a more finely pinned drafting machine 14, with a suitable number of ends up, for example four. The product of the final pin drafter 14 may either be spooled or supplied to a can, according to the preferred operation, from which the sliver is applied preferably to a cone rover 15, the output of which is spooled and in turn supplied to the drafting and spinning frame 16.

Each of the pin drafters 11 to 14 inclusive, comprises briefly a set of faller points 17, adapted to be moved in the direction of the arrow 18 with means for delivering thereto a plurality of slivers or of strands of fiber 19 from cans 21. Drafting rollers 22, 23 and 29 are provided for drawing the consolidated sliver 24 through the faller points 17 and delivering them through condensers 25 and 26 to a conventional coiling head 27 of a receiving can 28. The arrangement is such as to maintain fiber control at all times during the passage of the fiber and especially to hold or support the fibers at closely spaced points wherever the fibers are being worked. For example, for the sake of more closely nipping the fiber after leaving the faller points 17, the nip roll 29 of relatively small diameter is placed in very close proximity to the delivery end of the bed of faller points 17 so as to press the fibers against the upper draft roll 22 and thereby provide a closer nip than could be obtained from the larger diameter rolls 22 and 23. The general arrangement of the pins or faller points in the faller point bed 17, the method of moving them, and the principle of operation involved are conventional. For example, the arrangement may be similar in general to that described in the Holdsworth patents, Numbers 722,984, 1,847,331 and 1,394,829 relating to gill box structure. Specifically, however, the pin-drafting apparatus differs somewhat from conventional arrangements. A more detailed description of these differences, as well as an explanation of the relationship between the characteristics of the several pin drafters 11 to 14 inclusive, will be given in greater detail hereinafter.

Satisfactory results have been obtained by employing apparatus taking either of two different forms to serve as the cone rover 15, indicated schematically in Fig. 1. For example, I may employ a conventional type of cone rover, employing roller drafting and driven flyers in connection with bobbins, on which the rovings are wound. Such a cone rover may be of the type, for example, illustrated in Fig. 84, on page 258 of "Manufacture of Woollen and Worsted Yarns," by J. W. Radcliffe (second edition), published in 1924 by Emmott and Co., and described in chapter 20, pages 229 to 247 of Radcliffe. In this case the final pin drafter 14 is preferably of the type known as a spindle gill arranged to produce a minimum twist for which a spindle gill is capable of adjustment. Such a spindle gill includes a bed of faller points 17, as indicated in Fig. 2, with a driven flyer winding the sliver 24 on a drag bobbin instead of employing a receiving can 28. The flyers, however, are driven at such speeds as to produce relatively little twist in comparison with previous practice in worsted drafting.

Alternatively the cone rover 15 may take a modified form employing a carrier apron drafting head with a flyer spinner adjusted for very little twist. In this case, the cone rover is fed from rotating cans instead of from a plurality of

wound bobbins carried on a creel board. Accordingly, the final pin drafster 14 will then be of the type illustrated in Fig. 2, feeding the sliver 24 into the receiving can 28. For a maximum degree of loftiness and softness of fiber desired, the latter type of cone rover is advantageous inasmuch as the delivery cans may be set for a negligible speed of rotation so as to impart substantially no twist to the sliver processed by the rover. Supplying the rover from rotating cans has the further advantage that with a set condition of the aprons, the amount of twist can be adjusted to suit the condition of the aprons and to suit the condition of the stock. The apron drafting head employed in such a cone rover may be of the type which will be described in greater detail in connection with drafting and spinning frames 16, except that in the cone rover, I preferably employ a drafting head in which the carrier aprons are substantially horizontal instead of nearly vertical.

The drafting and spinning frame 16, indicated schematically in Fig. 1, includes a plurality of drafting heads and spinning bobbins as illustrated in Fig. 3. Such a drafting head, illustrated for example in Figs. 4 and 5, comprises briefly a pair of conveyor and ratch rolls 31 and 32, the rear roll 31 being driven; a pair of draft rolls 33 and 34, the rear roll 33 being driven; and a pair of carrier aprons or belts 35 and 36, driven from the upper end in a manner which will be described more in detail hereinafter. A significant feature of the carrier aprons 35 and 36, where the apparatus is to be employed for drafting worsted, is the space shown at 37 in Fig. 4 between the confronting surfaces of the belt or apron at the upper end of the aprons 36 and 35. The invention is not, however, limited to the use of this spacing 37, and in drafting certain types of fibers, this feature may be eliminated. Snubbing bars 38 and 39 are provided for causing the confronting contact portions of the belts 35 and 36 to follow a serpentine path. Relatively narrow guide bars or strips 41 and 42 are provided at the lower ends of the belts 35 and 36 in place of rollers in order to permit the provision of fiber control at the lower end of the carrier aprons relatively close to the nip of the draft rolls, and also in order to provide for a soft pliable control at this lower end.

The conveyor or ratch rolls 31 and 32 are arranged for feeding a sliver 45 to the aprons 35 and 36. The draft rolls 33 and 34 are arranged for drawing a reduced strand 48 from the aprons 35 and 36. The surface speeds of the pair of rolls 31 and 32, the pair of aprons 35 and 36, and the pair of rolls 33 and 34 are progressively greater so as to effect a desired degree of drafting. Various details of construction and additional advantageous features of the apron type drafting head will be described hereinafter.

As indicated in Fig. 3, a conventional type of spinning throstle of the ring type may be employed, having spindles 51, driven by belting, not shown, engaging wharls 52 and winding yarn upon bobbins 53. The yarn is drawn through guide eyes 54 and travelers 55 carried by rings 56. Suitable conventional mechanism, not shown, is provided for raising or lowering either the rings 56 or the spindles 51 for distributing the yarn on the bobbins 53.

The worsted process for a given batch of fibers is set up for a predetermined number of passages through pin-drafting machines, all essentially the same as illustrated in Fig. 2. Two to four pas-

sages are usually sufficient to produce a level end in the product yarn, and this is typical of the process of the present invention. The number of ends fed into each passage of the pin drafsters will depend upon the number of doublings predetermined as being desirable for producing the desired blending in the passages. Six to eight ends are typical for any given passage, and the doublings for producing a given worsted yarn may be from 200 to 1,000, depending upon the blend of fibers in the batch. Drafts ranging from between 5 to 1 and 8 to 1 are typical for each passage, the draft of each passage being predetermined to level the strand and to reduce it the desired amount. The reduction through the several passages is to level and reduce the product strand through the last pin-drafting machine to a size suitable for the roving frame.

Under the prior art there are two principal systems for fabricating worsted yarns, known as the English or Bradford system and the continental or French system. Other systems are modifications of either of these or the combination of practice in both.

Under the English system, which is the simpler and less costly of the two, there are usually four or five successive passages through gill boxes from the comb followed by four or more successive passages through drawing frames followed by finishers, reducers and rovers. The latter drawing frames do not include gilling mechanism, and each operates to produce a product strand which is twisted and is wound on bobbins in twisted condition. In the later passages, in which the product strand is packaged in twisted condition for transfer to the next operation, there is a high percentage of piece-up waste.

The process of the present invention is more nearly comparable with the English system. These passages of the English system in which the product strand is twisted are not included in the new process, and there is no loss of fibers in piece-up waste. For production of comparable yarns, there are no more passages through gill boxes and ordinarily fewer passages under the process of the present invention than there are under the English system.

The other well known prior art system, known as the French system, uses finer grade fibers, and produces a loftier yarn, than the English system, which was devised as a worsted process for using all grades of fibers. The process of the present invention is capable of using all grades of fibers. The product yarn of the new process has a loftiness, quality and texture comparable with a yarn of the French system.

The French system as a process is not readily comparable with the process of the present invention. One characteristic feature of the French system is the employment of many passages through mechanisms known as porcupine rolls, these revolving rolls having steel pins arranged around the periphery. The French system requires many more operations than the English system, ranging from 9 to 14 passages under the French system, depending upon the grade of yarn desired as compared to 7 to 9 passages under the English system. The French system is, therefore, inherently more costly than the present invention.

The following are comparative tables of typical operations under the English system and the new process for producing yarns of comparable count;

*Typical steps under
the English or Bradford system*

OPERATIONS AFTER THE COMBING MACHINE

Operation	Number of Ends	Draft	Doublings	Machine	Remarks
Combing Mill:					
1.....	18-24	7X1	18-24	Intersecting gill box. False twister to can.	1st finish gilling of tops.
2.....	4-6	6	72-144	Intersecting gill box. False twister, baller.	2nd finish gilling of tops. Product is tops.
Yarn Processing:					
3 (1).....	5-6	6	16	Intersecting or open gill box. False twister to can.	1st gilling operation. If different types of fiber are blended, it is done in Blending Box.
4 (2).....	6	6 to 7	36	Two spindle intersecting or open gill box. Flyers Bobbin.	2nd gilling operation.
5 (3).....	5	6	180	Open drawing box, twister, Flyers Bobbin.	3rd Drawing Box.

4.....	4	7	720	Intersecting gill box. Coiler to can or to spindle drifter.	
5.....	1	7.5	.....	Cone Rovier. Preferably.....	Product is roving, slightly twisted.
6.....	1	7 to 14	.....	Ring, Cap or Flyer spinning frame.	

NOTE.—The operation listed above as third is so listed for better comparison with the present invention. Ordinarily, the first two operations are considered preliminary to drafting; and operations 3 to 10 are considered as the first to eighth operations in drawing from "tops" to yarn. Doublings are counted from operation 3 (1), doublings in gilling of tops being disregarded.

In any drawing frame passage which does not embody a pin-drafting machine, for example in the passage of the spinning frame, it is advisable also to maintain continuous fiber control throughout the length of the drafting area.

Pursuant to this purpose, in accordance with my invention I provide fiber control mechanism which extends to close proximity with the front drafting mechanism. For example, in a spinning frame, comprising a set of front drafting rolls, and a set of back rolls or feed rolls, I preferably provide carrier aprons instead of carrier rolls between the front and back rolls, the carrier aprons extending towards the front drafting rolls to close proximity with the nip thereof.

The pin-drafting machine, illustrated in Fig. 2 schematically, may take any suitable form and is not limited to the specific arrangement illustrated. Preferably, intersecting pins are employed as in intersecting types of gill boxes. For the sake of simplicity, however, only one set of faller bars 17 is represented as in an open type of gill box. There are guide rollers 57 and 58 for delivering slivers 19 from a plurality of supply cans 21 to a delivery apron or belt 59. There may be a weight or tension roller 61 for pressing the slivers 19 into a combined mass 62 carried by the delivering apron 59.

In conventional worsted gill box assemblies there are usually movable ratch rolls mounted in a position approximately corresponding to that of the right-hand apron-carrying roller 60. Such ratch rolls acting in conjunction with the faller bars 17 and the draft rolls 22 and 23 provide the

desired draft of the fibers. In such a case, the faller bars 17 are progressed in the direction of motion of the fibers at a speed intermediate the surface speed of the ratch rolls and the drafting rolls. In carrying out my invention, however, I prefer to omit such ratch rolls and to obtain the entire drafting effect as a result of drawing the fibers through the faller pins 63 by means of the draft rolls 22, 23 and 29. To this end the length of the faller bed 17 in the longitudinal direction, that is, in the direction of motion of the fibers parallel to the arrow 18, is made somewhat longer than it is customary in the conventional gill boxes. It is to be understood that the drafting rolls 22 and 23 and the nip roll 29 have a higher peripheral speed than the linear speed which the pins 63 in the faller bed 17 are progressed.

The condenser 25 comprises a trumpet having a throat 64, a longitudinal section of which has the shape of outline indicated in Fig. 8B. The throat has a circular cross-section as indicated in Fig. 9B. Preferably a convex surface guide bar 65 is mounted in advance of the condenser 25 in such a manner that the strand 24 is caused to rest upon the guide bar 65 prior to entering into the throat 64 of the condenser 25. As indicated in Fig. 8A, the guide bar 65 may be pivoted upon a shaft 66 which is interconnected or linked in a manner not constituting a part of the present invention with a stop motion serving to stop delivery of the sliver to the machine in the event of breakage. A light, balance or spring mechanism, not shown, is provided where the guide bar 65 is to be employed in conjunction with a stop

mechanism. I have found that it is unnecessary to cause rotation of the condenser 25 although a rotating type of condenser may be employed if desired.

Heretofore in processing worsted through gill boxes it has been customary to impart an appreciable twist to the sliver after it leaves the faller points in order to provide adequate tensile strength to the sliver for handling preparatory to the next operation. However, in order to preserve the loftiness of the yarn and the parallelism of the fibers, I avoid such twisting. Nevertheless, I maintain adequate strength of slivers so that they may be handled in the receiving end delivering cans and passed through a succeeding operation, such as an additional pin-drafting operation or a cone-drawing operation. In order to avoid adhesion between successive coils of sliver in a supply can, I provide condensers 25 and 26 so designed as to fold in the selvage of the sliver and eliminate wild fibers or unevenness at the selvage. The condenser 26 has a throat 67 of elliptical cross-section, as shown in Fig. 9C. Preferably, the condenser 26 is so mounted that the major axis of the ellipse 67 is horizontal, where the flattened sliver 24 lies substantially in a horizontal plane in its passage through the faller points 17 and the draft rolls 22 and 23.

The draft rolls 22 and 23 compress the fibers so that the strand 62 formed from the combination of slivers 19 is flattened to a single tape-like strand 24. In passing over the convex upper surface of the polished guide bar 65 the strand 24 is given a slight crescent shape with drooping sides or selvage, as indicated at 68 in Fig. 10A. The minimum throat diameter of the condenser 25, shown in Fig. 9B, is less than the width of the flat sliver 68, shown to a larger scale in Fig. 10, so that in passing through the trumpet 64 the selvages are gradually folded in and the sliver has a shape 69, indicated in Fig. 10B, after passing through the throat 64. In the passage of the sliver toward the throat 67 of the elliptical condenser 26, the selvages are curled in, as indicated at 71 in Fig. 10B'; and after passage through the elliptical throat 67, the selvages are further curled, as indicated at 72 in Fig. 10C. In this manner the fibers are condensed and the selvages are protected. As a result of this treatment of the output of the pin-drafting machine and the continuous fiber control, maintained in the course of continuous operations, the fibers may be retained parallel and it is unnecessary to impart any twist to them, especially during the pin-drafting operations. It will be understood that as the sliver is coiled by the coiling head 27 and drops in progressively displaced coils around the inner surface of the receiving can 28, the edges of one portion of the sliver tend to come in contact with the edges of another portion of the sliver and the folding-in of the selvages is, therefore, advantageous as it eliminates adhesion by the successive coils when the sliver is being drawn from the can after the can becomes a supply container corresponding to one of the cans 21 in a subsequent stage of the pin-drafting machines or in connection with an operation following pin drafting.

It is accordingly unnecessary to provide means for supplying a false twist to the product strand 72 delivered to the can 28. The supply sliver containers or cans 21 contain the product strands of the next passage, each container 21 comprising a supply end packaged in the manner hereinbefore described. As many supply sliver cans

21 are placed at the feed end of the pin-drafting machine as there are ends required to obtain the desired number of doublings in the incident passage.

5 The strand 62 may contain some fibers which are so short as not to extend across the gap between the bed of faller points 17 and the nip of the drafting rolls 22 and 23. The bulk of the fibers in the strand, however, operates to carry 10 fibers along into the drafting rolls, including fibers which are shorter than the gap. Another factor to be considered is the tendency of the short fibers to lose parallelism due to working the strand in the drafting operation, and there 15 is the companion tendency for short fibers to fall out of the strand, these being lost as fly waste. The use of a longer faller bed together with the close proximity of the inner nip roll 29 to the faller bed, in accordance with my invention, minimizes the tendency of the short fibers to lose 20 parallelism and to fall out of the strand.

Under prior art practice, the nip of the drafting rolls of a Bradford roll drafting frame is usually located 2" or more away from the control 25 rollers of the frame. Therefore, the percentage of fibers which are so short as not to span the gap between the support points and the nip of the drafting rolls is high. Accordingly, the 30 tendency of fibers to lose parallelism is great, and there is a relatively high percentage of fiber lost as fly waste. More important, control of the fibers is partially relinquished in the critical drafting area, causing bunching, which produces 35 unevenness of the product strand of the incident passage. For this reason, under prior art practice, relatively many passages, including doublings, are deemed necessary to attain a level end, or the desired degree of uniformity in the final product yarn.

40 In carrying out the present invention, the nip of the drafting rolls 22 and 23 is positioned much closer to the retreat end of the bed of faller points 17 than under Bradford practice. The gap between the faller points and the nip of the set of drafting rolls is preferably $\frac{3}{4}$ " to $1\frac{1}{2}$ " as compared to the 2" or more under Bradford practice.

45 A greater percentage of fibers in the strand 62, therefore, are long enough to span the gap between the bed of faller points 17 and the nip of the set of drafting rolls, to thus be under positive control of the faller points 17 while they are being drafted. The corresponding smaller percentage of fibers in the strand 62 is so short as 50 not to span the gap between the draft rolls and the faller points, and this reduced percentage of short fibers is so low that there is a greatly reduced and negligible loss in fly waste in practicing the present invention. A more important 55 result, as previously noted, is that the product strand of each of the several passages is more uniform because of continuous fiber control in the drafting area.

60 It should be understood that the gap between the bed of faller points 17 and the nip of drafting rolls 22 and 23 need not be reduced to less than the length of the shortest fibers in the sliver. There is mutually cooperative fiber control between fibers, incident to the lateral thrust exerted by fibers upon each other. Those fibers which do not span the gap between the bed of faller points and the nip of the drafting rolls are, therefore, maintained under continuous 65 control throughout the length of the drafting

area, the control being exercised by the bulk of the fibers in the strand.

Under preferred practice, the pins 63 in the faller bed 17 are stepped up slightly in speed about 3½% to 5% over the linear speed of the belt 59. The drafting rolls 22 and 23 are driven at a speed greater than the travel of the faller pins which is predetermined to produce the desired degree of attenuation in the product sliver of the incident passage. The amount of draft and the number of doublings to be used depend upon the type of fiber handled and the characteristics desired in the yarn to be produced. Nevertheless, for the sake of illustration, numerical values of drafts successfully employed in successive pin-drafting machines have been indicated in the schematic diagram of Fig. 1.

The normal intersecting types of gill box used in the Bradford system have approximately a four-inch upper bed and a six-inch lower bed, with 8 to 16 pins per inch measured cross-wise, the bed length being measured longitudinally. In carrying out my process, however, I employ pin drafters in which both the upper and lower beds extend up to nine inches in the direction of stock travel and no ratch rolls are employed.

At present, it is believed best results are obtained by employing at least 22 pins per inch in the faller bars and as many as 29 pins per inch may be employed. A coarser pinning may be employed for coarser grades of stock. As indicated also in Fig. 1, the pin-drafting machines 11, 12, 13 and 14 may be successively more finely pinned. For a 64-grade wool, the best pinning is now believed to be 22 pins per inch in the pin drafters 11, 12 and 13 and 29 pins per inch in the pin draftr 14. For fine stock and light slivers, it is advantageous to use finer pinning per inch in the successive pin drafters than above indicated.

The invention is not limited to this particular arrangement but has been found to give satisfactory results, for example, when the first and second pin-drafting machines are supplied with six ends up and the third pin draftr 14 with five ends up and the fourth pin-draftr machine with four ends up.

The drafting heads, such as illustrated in Fig. 4, are mounted in two rows on either side of the spinning frame above banks of spindles 51 on either side of the frame in an arrangement similar to that customarily employed in conventional frames having roller drafting heads. Such spinning frames have two inclined-surface rails or supports running the length of the frame on either side, one of which is represented in cross-section at 73 in Fig. 4. As indicated in Fig. 3, these spindles 51 are mounted in a bank below each row of drafting heads. Preferably the drafting heads are mounted in pairs or as twin units 74 as represented in Fig. 3. The aprons of each twin unit 74 have a common power drive connection and are mounted so as to be removable in pairs as will be explained more in detail hereinafter.

Each twin unit 74 has common feed rolls 31 and 32 and individual draft rolls 33 and 34 as indicated in Figs. 3 and 6. The feed rolls, which may also be called back or feed rolls or ratch rolls, include the power driven rear or inside roll 31 and the freely running outside roll 32. Likewise, the drafting rolls 33 and 34, which may also be called delivery rolls or front rolls, include the power driven inside or rear roll 33 and the freely running friction-driven outside roll 34. There is

a common drive shaft 75 running the length of the spinning frame for all of the feed rolls 31 on one side of the frame and, likewise, a common drive shaft 76 for all the draft rolls 33 on the same side of the frame. The aprons 35 and 36, however, are not directly driven from common shafts running the length of the frame. Instead to facilitate removal of the apron mechanism in twin units without necessitating the disassembly of the parts of the twin unit, an auxiliary apron driving shaft 77 is provided which runs the length of the spinning frame. Means are provided in each unit 74 for driving all four aprons, that is, the rear aprons 35 and the outside aprons 36 from the drive shaft 77 through a separate drive gear 78 for each unit 74. It is to be understood that a suitable gear box 79 is provided for driving shafts 75, 76 and 77, including the requisite change gears for changing roller speed ratios, if desired, and suitable mechanism, not shown, is also provided for driving the spindle wharls 52 through bands, not shown, running at suitable speeds in relation to speeds of the shafts 75, 76 and 77.

As represented in Figs. 6 and 7, each twin unit 74 has a separate supporting frame or casting including side plates 81. The side plates 81 include flanges 83 by means of which they are removably mounted upon the front surfaces of uprights or brackets 84 bolted to the lengthwise running frame members 73.

For driving the aprons 35 and 36, drive rolls 85 and 86 are provided, two drive rolls 85 being mounted upon a common drive shaft 87 and two drive rolls 86 being mounted upon a common drive shaft 88. The shafts 87 and 89 carry intermeshing gears 89 and 90 midway the drive rolls 85 and 86. The rear gear 89 in turn meshes with the drive gear 78 carried by the common apron drive 77. In order to drive the belts 35 and 36 without tension so as in effect to push the belts instead of pulling them as in an ordinary pulley drive, squeeze rolls 91 and 92 are provided which are carried by hollow shafts 93 and 94 journaled in floating bearings 95, resiliently clamped together by a bolt 97 having a coil spring 98 mounted under a tension-adjusting nut 99. The belts or aprons 35 and 36 are composed of any suitable material such as leather or rubber impregnated and covered fabrics such as used in industrial rubber belting. Preferably, rubber belting is employed as such material may be obtained with ends bonded together without changing the thickness to form endless belts. The belt material has sufficient resiliency so that it tends to take a form with the bends having the greatest possible radius. Consequently, if mounted loose enough not to be under tension, as described, the belts will move with their inner confronting portions traveling toward and through the space between the guide bars 41 and 42 in response to the driving action of the rolls 85 and 86 and the squeeze rolls 91 and 92. No tension will be put in the outer portions so that the belting is not pulled by the drive rolls, but the inner confronting portions of the belting are pushed.

The supporting shafts 87 and 88 for the apron drive rolls 85 and 86 are also hollow and all four shafts 87, 88, 93 and 94 are designed to rotate freely upon fixed supporting shafts 101, 102, 103 and 104 respectively. The fixed shafts 101 to 104, inclusive, have square ends 105 to 108, respectively, as shown in Fig. 7. The shaft ends 105 and 106 are eccentric with respect to the axes of the fixed supporting shafts and the hollow shafts.

For receiving the square ends 105 to 108 inclusive, keyhole shaped slots 109 are provided in the side plates 81 of each twin unit 14. Each such keyhole slot 109 has a circular portion 111 of greater diameter than the diagonal dimension of the cross section of the square shaft end and has a parallel sided portion 112 sufficiently wide to make an easy slide fit with one of the square ends 105 to 108. Accordingly, the spacing between the confronting surfaces of the aprons 35 and 36 may be varied by rotating the eccentric square ends 105 or 106 to any of the four different possible positions, since this operation varies the spacing between the axes of the apron driving rolls 85 and 86. In this manner the space 31 between the confronting surfaces of the aprons 35 and 36 at their feed end may be varied in order to vary the softness of the control or to accommodate the apparatus to slivers of varying thickness in order to make sure that fiber control of the sliver is maintained without introducing any nip, and without applying any drag prior to reaching the snubbing bar 38. It will be observed that for any of these settings of the axes of the apron-supporting rollers, the spacing between the axes is greater than the sum of the radii of the rolls and the thickness of both aprons so that space remains between the confronting surfaces of the aprons at the feed or entry end thereof where the strand is received from the feed rolls 31 and 32.

Although the apparatus illustrated is especially useful in the drafting of worsted fibers, the invention is not limited thereto and may be employed also in connection with other classes of fibers. It is well known to those skilled in the art that worsted and woolen fibers should not be drawn twice in the same direction. Accordingly inter-draft is not ordinarily employed in the drafting of worsted or woolen fibers. However, some fibers such as cotton, for example, may successfully be drafted twice in the same direction and inter-draft may be employed. The adjustable arrangement, described for varying the lateral spacing of the apron drive rolls 85 and 86, permits also providing a close nip at the upper or feed end of the aprons 35 and 36. Accordingly, the apparatus illustrated is adaptable for use, if desired, in connection with inter-draft of suitable fibers such as cotton fibers. In this manner very high draft ratios may be obtained by drafting successively from the ratch rolls 31 and 32 to the aprons 35 and 36 and again from the aprons 35 and 36 to the draft rolls 33 and 34 (Fig. 4).

In the drafting of worsted, however, the inter-draft adjustment is not employed and I consider it important to maintain the spacing 37 at the feed end of the aprons 35 and 36. Consequently the effective length of ratch is the entire distance between the line of contact of the feed rolls 31 and 32 and the line of contact of the draft rolls 33 and 34. This length of ratch may be made longer than the length of the longest fibers in the strand 45 without at any time losing control of the shorter fibers and without failing to provide lateral compression of the strand to support the shorter fibers. The serpentine path, followed by the strand 45 after passing the snubbing bar 38, gives progressively increasing compression and lateral thrust upon the fibers. Since the aprons 35 and 36 are not maintained under tension, but are in effect, pushed rather than pulled by the drive rolls 85 and 86 they are relatively loose and pass loosely over the guide bars 41 and 42 so that even at the lower end of the aprons 35 and 36

the fibers are not gripped so tenaciously so as to result in rupture of the longer fibers of the draft caused by the grip of the draft rolls 33 and 34. The apron surfaces are held against the strand by the resilience of the apron so as to hold the strand softly like a glove. The serpentine path of the aprons 35 and 36, on either side of the snubbing bar 39, gives progressively increasing frictional drag to the strand being drafted, to assure maintenance of all fibers in parallel condition.

In order that this frictional drag may be adjusted or that the snubbing effect of the snubbing bars 38 and 39 may be adjusted, these bars are also adjustably mounted. As illustrated in Fig. 6, notches 113 varying in depth are cut in the snubbing bars 38 and 39 so that by varying the longitudinal position of the bars 38 and 39 in supporting slots 114 and 115 in the side plates 81, any desired adjustment may be obtained. Similar notches 116 of varying depth are provided in the top edges of the lower end apron guide rails 41 and 42 in order to permit requisite adjustment in case of slight variations in belt lengths or to vary the lateral compression effect at the lower end of the aprons 35 and 36.

To facilitate easy removal of the twin apron units as a unit, the supporting flanges 83 at the sides of the side plates 81 are also provided with button-hole or keyhole shaped slots 117, cooperating with readily loosened screws 118 threaded into the vertical supporting brackets 84. Preferably the flanges 83 carry locating pins 119 cooperating with complementary sockets 121 in the vertical bracket surfaces 84.

The common apron drive shaft 71 is carried in a bearing block 122 having a slot 123 for receiving the shaft 71 and a cover 124 adapted to be screwed to the block 122 for closing the slot 123. Thus the shaft 71 is readily removed.

Similar arrangements are provided for supporting the feed and draft roll drive shafts 75 and 76, as shown in Fig. 7. There is a bearing block 125 bolted to the bracket 84 having a slot 126 for the drive shaft 76 with a securing plate 127. For carrying the feed roll drive shaft 75 there is a bearing block 128 bolted to the bracket 84 having a slot 129 for the shaft 75, adapted to be covered in this case by a second bearing block 131 having a slot 132 for receiving the supporting shaft 133 of the outer or friction driven feed roll 32. Although not clearly evident in the drawing owing to the scale employed, the slot 132 is slightly inclined so that the shaft 133 in the roll 32 tends to roll downward and inward against the driven roll 31. The friction driven draft roll 34 is also provided with supporting stub shafts 134 adapted to rest on an inclined edge 135 of a projecting portion of the lower bearing bracket 125. Felt-covered clearer rolls 136 and 137 may also be provided for removing lint from the surface of the draft rolls 33 and 34, respectively. The clearer roll 137 is shown as carried by stub shafts 138 riding on the same inclined surface 135 and the clearer roll 136 is mounted in a conventional linkage 139, illustrated in Fig. 4. If desired, a yoke 141 biased by a spring 142 under the adjusting nut 143 and a yoke-carrying pin 144 may be provided for releasing the draft roll 34 in response to a stop motion (not illustrated in Fig. 4) in the case of breakage of the sliver 45.

The bearing bracket 131 for carrying the friction driven feed roll 32 is interchangeable with a modified bearing bracket, illustrated in Fig. 11, for use when it is desired to incorporate a quick

acting automatic stop motion in an apron drafting head 74.

Preferably the strand 45 is supplied to the feed rolls 31 and 32 through a condenser 145 which is attached to a traverse rod 146, and may be of the trumpet type. The rod 146 is reciprocated a predetermined amount longitudinally of itself, that is cross-wise with respect to the direction of travel of the roving 45, by driving means at the end of the frame. Such driving means is known to those skilled in the art and is, therefore not shown. In this manner the condenser 145 serves to traverse the strand 45 widthwise of the drafting mechanism of Fig. 5 to distribute wearing action of the strand 45 on the parts to prevent concentrated wear of the control aprons 35 and 36, and of the feed and draft rolls 31, 32, 33 and 34.

It will be noted that the lower edges of the 20 lower guide rails 41 and 42 of the aprons 35 and 36 are close to the nip of the drafting rolls or delivery rolls 33 and 34. The aprons extend substantially into the space bounded by the cylindrical surfaces of the drafting rolls 33 and 34 and an imaginary plane, not shown, tangent to both of these cylindrical surfaces. Such an imaginary plane would intersect the aprons 35 and 36. The drafting area extends from the nip of the feed rolls 31 and 32 to the nip of the delivery rolls or draft rolls 33 and 34. The actual extent of the drafting effect depends upon the length of the fibers in the roving 45. Each fiber, as it passes into the nip of the drafting rolls 33 and 34, is subjected to frictional resistance or retardation exerted by reason of lateral pressure or thrust by the opposed surfaces of the aprons 35 and 36.

Because of the close spacing between the nip of the drafting rolls 33 and 34 and the apron 45 guide rails or bars 41 and 42, a relatively small percentage of fibers in the roving 45 is so short as not to span the gap between the aprons and the nip of the drafting rolls. The short fibers which do not span the gap are carried along by the relatively high percentage of fibers in the strand which are long enough to span the gap. By this means the shorter fibers are maintained under fiber control as they travel across the gap. The result is negligible loss of fibers as fly waste, which evidences the more important result attained, of continuous fiber control being maintained on all the fibers of the roving 45 throughout the length of the drafting area.

The spacing between the opposed surfaces of the drafting aprons 35 and 36 is adjusted to produce the desired degree of tension on the fibers 55 of the roving 45. The adjustment is made, as previously explained, by setting the eccentric shaft means 105 and 106 and the snubbing bars 114 and 115 in order to provide the desired gradient of spacing between the apron surfaces longitudinally of the travel of the roving 45, and to provide the desired degree of snubbing action. The adjustment is made in accordance with the quality of the roving, the fibers which comprise the roving, and the count of yarn to be produced.

The shaft 75 is driven at a predetermined speed to drive the feed rolls 31 and 32 at a surface speed to travel the roving 45 at the desired predetermined speed of travel. The shaft 77 is driven at a predetermined speed to drive the aprons 35 and 36 at a surface speed sufficient to receive the roving 45 as quickly as it is delivered by feed rolls 31 and 32. The preferred practice is to step up the linear speed of the aprons 35 and 36 slightly, up to 10%, for example, and this is accomplished 70

in the gear ratio of the inter-gearing between the shafts 75 and 77, such gearing being consolidated within a gear box 79. The increase in linear speed should not exceed the maximum recovery value of the stock, which is about 10% in most types of worsted stock, and may be as little as zero in some types of synthetic fibers, such as rayon.

The shaft 76 is driven at such a speed as to drive the draft roll 33 with the required higher surface speed than the speed of travel of the aprons 35 and 36 and higher than the speed of travel of the strand 45 through the feed rolls 31 and 32 to produce the desired amount of attenuation of the roving 45.

According to one practice, the roving 45 which serves the spinning frame, can be the product strand of the last passage through pin drafting machines, such as illustrated in Fig. 2, the roving being fed to the spinning frame directly from the cans 28 in which it is received from the pin-drafting machine. Under this practice, there is no twist applied to the roving in any stage of the worsted process up to its being spun, and the product is a lofty yarn, having a texture similar to the product yarn of the French system.

Nevertheless, it does not follow that twisting the strand at some stage in the worsted process will invariably defeat the purpose of producing a lofty yarn. A slight twist applied to the product strand of one or more operations in the process will not detract from loftiness of the yarn to any noticeable or appreciable extent.

As already explained, if the last pin-drafting machine 14, indicated in Fig. 1, is of the spindle gill type, a twist of a fraction of a turn per inch, e. g., two-tenths turn per inch, may be employed and an additional twist of up to approximately one and one-half turns per inch may be provided in the cone rover 15. The twist used in this system is slightly less than one-half that normally used in the Bradford system.

On the other hand, if the last pin-drafting machine 14 is arranged to provide no twist and if a cone rover is employed, the cone rover may be of the type employing apron drafting heads similar to those illustrated in Fig. 5, except that ordinarily in the cone rover it is more convenient to arrange the aprons with substantially horizontal confronting surfaces and to arrange the feed rolls and draft rolls accordingly for substantially horizontal travel of the sliver before being delivered to the flyers. In this case, the cone rover is supplied with sliver from rotating cans instead of bobbins. As little twist may be imparted by rotation of the cans as desired, e. g. from one-tenth to five-tenths turns per inch.

Experiments determined that twists as low as 0.5 turn per inch operated satisfactorily as supply ends in the spinning frame, the rovings withdrawing from the bobbins evenly, and without drafting. Twists up to 1.0 turn per inch produced yarn of the same loftiness and quality as comparable yarns spun from untwisted rovings. Higher degrees of twist up to 1.50 turns per inch did not show appreciable increased hardness in the product, and twists of 2.5 to 3 turns per inch, which are comparable with the practice of the prior art worsted process, produced a yarn of much greater loftiness, and finer quality, than yarn fabricated under the English system.

In a sliver or roving which is entirely without twist, the fibers are arranged parallel and directed longitudinally of the strand. By twisting the strand, the fibers continue directed sub-

stantially longitudinally of the strand until a twist is applied of relatively high magnitude, for example, such as is applied under the prior art worsted process. A low degree of twist of the product strand of a passage in the worsted process will not operate to disarrange the fibers of the strand from disposition longitudinally of the strand, to any substantial extent.

It can be, therefore, stated as a general conclusion that loftiness and fine quality texture is attained in the product yarn of the process of the invention when the strand of fibers is maintained in substantially untwisted condition throughout the several operations until the yarn is spun, and this statement applies in the case of the product strand of one or another passage being slightly twisted.

Although a stop motion may be provided to reduce lap waste, very few breakages occur and it is seldom necessary for the attendant to splice or lick in rovings.

Nevertheless, if desired, a stop motion may be embodied in the apron drafting apparatus, as illustrated in Figs. 11, 12 and 13. For this purpose the bearing block 131, shown in Fig. 7 for supporting the free-running feed roll or outside feed roll 32, is replaced by a linkage for braking the feed roll 32 and lifting it away from the strand, in the event of breakage, in order to avoid delivery of further strand to the aprons 35 and 36. In addition, a delicately balanced switch carrying a guide eye, is provided at the lower end of the apron drafting head in order to actuate the feed roll braking and lifting means in response to breakage of the strand.

For supporting the linkage controlling the feed roll 32 and other associate mechanism, a frame 147 is mounted between each pair of uprights 84 carrying one of the twin drafting heads 74. The frame 147 comprises side arms 148 and a cross member 149. A center arm 151 is secured to the cross arm 149.

The side arms 148 and the center arm 151 have ears 152 in which are pivoted bell crank levers 153 with forwardly extending handles 154 for effecting manual resetting. Depending from the pivot points of the bell crank levers 153 are crank arms 155. At the lower end of each crank arm 155 there is pivoted a brake rigging 156. Each brake rigging comprises a brake bar 157 extending laterally to the rear of the peripheral surface of the free-running feed roll 32 with which it is associated. Each brake bar 157 is secured at the ends to a pair of curved links 158. Each curved link 158 is pivoted at the end opposite the attachment of the brake bar 157 to the lower end of the crank arm 155 at a pivot point 159. The links 158 are curved upwardly and have a concave under edge 161 adapted to ride over the stub shaft 133 of the feed roll 32. Small bearing blocks 162 screwed or otherwise secured to the forward end of the frame side arms 148 are provided for supporting the stub shafts 133.

Shelves 163 are provided at the angles of the side arms 148 and 149 and have openings 164 therein adapted to receive vertically slideable rods or bars 165 with a loose slide fit. There is a bell crank 153 and a brake bar 157 for each of the ratchets 32 and likewise a crank-operating bar 165 for each of the cranks 153. At the upper end, each crank-operating bar 165 is pivoted to the rear end of one of the bell cranks 153, preferably by means of an elongated opening 166 (Figs. 11 and 12) in the bifurcated rear end por-

tion 161 (Fig. 13) of the bell crank 153 and a cross pin 168 secured in the upper portion of the bar 165.

The lower end of each bar 165 has a collar 163 secured thereto. A compression spring 171 is mounted between the collar 169 and the shelf 163 for depressing the bar 165 and drawing the crank arm 155 forward to break and release the feed rolls 32.

Each bar 165 has a socket or notch 172 therein adapted to cooperate with the nose or detent portion 173 of a pin 174 horizontally slideable in the shelf portion 163 of the frame 147. The detent 173 is spring biased by means not shown to engage the notch 172 in the bar 165 for holding the brake bar 157 out of the operating position until the detent 173 is retracted.

The frame 147 also has rear wings 175 supporting solenoids or electro-magnets 176 each of which has an armature 177, shown in Fig. 12 but omitted for clarity from Fig. 13. Each such armature 177 is pivotally joined to the end of the detent for retracting it from the notch 172 in response to energization of the solenoid 176. The solenoid 176 is adapted to be connected to a suitable source of energizing current 178 by means of leads 179 and 180.

For controlling the energization of the solenoid 176, a switch 181 is provided which may be of any suitable type adapted to carry a delicately balanced lever arm 182 and to close an electrical circuit in response to relatively minute variations in weight resting on the lever arm 182. A guide eye 183 is mounted in the end of the lever 182. The drafted sliver 48 from the draft rolls 33 and 34 is threaded through the guide eye 183 in such a manner that the weight of the sliver 48 normally holds the lever 182 in the open circuit position of the switch 181, which is a so-called normally closed switch. The switch 181 may be of any suitable type responding to minute changes in pressure acting on the operating mechanism, such as switches of the type sold under the trade name of "Microswitch," for example.

The Micro-switch 181 has contacts connected in series with the solenoid winding 176 and the energizing leads 179 through a pair of conductors 184, and preferably also in series with a second switch comprising a stationary contact 185 and a movable contact 186. The stationary contact 185 comprises a button of conductor material, such as copper, mounted on the under side of the cross arm 149 of the frame 147, but insulated therefrom and connected through a conductor 187 to one terminal of the solenoid winding 176, the other terminal of which is connected to the current supply lead 179. For supporting the movable contact 186 an insulated bracket 188 is mounted upon the collar 169 at the lower end of the bell crank-operating bar 165. Preferably, the movable contact button 186 is carried at the end of a pin 189 slidably mounted in the bracket 188 and resiliently biased to the upward position by means of a compression coil spring 191. The lower end of the pin 189 is electrically connected to one of the leads 184 from the Micro-switch 181. The arrangement is such that the contact carrying pin 189 has considerable longitudinal play so that it is free to rise with respect to the supporting bracket 188 when the bell crank-operating bar 165 is in the lower or depressed position, as shown in Fig. 12, and is pressed toward the supporting bracket 188 when the bar 165 is in the upper or latched position represented in Fig. 11.

When the spinning frame is to be started up after a shut down or after the solenoid 176 has operated, the operator depresses the reset handle 154 thereby releasing the feed roll 32 from the brake bar 157 and allowing the feed roll 32 to ride in contact with the driven feed roll 31. This causes the feed rolls 31 and 32 to nip the strand 45 and causes the strand 45 to be fed through the aprons 35 and 36 to the draft rolls 33 and 34, from which the drafted strand 48 emerges. The operator passes the end through the guide eyes 183 and 54, the ring traveler 55 or cap or flyer and to the bobbin 53. Thereafter, as the sliver passes through the stop motion guide eye 183, the weight of the strand 48 is sufficient to hold the Microswitch 181 in an open circuit position. In depressing the reset handle 154, the operator will have caused the rod 165 to be lifted so as to permit the notch 172 therein to engage the detent 173 which is thus permitted to enter the notch 172 and lock the rod 165 and the bell crank lever 153 in the operating or drafting position of the drafting head.

In the event, however, that a defective strand 45 should be supplied to the feed rolls 31 and 32 resulting in a break 192 in the emerging strand 48, the switch-operating lever 182 will be returned to its normal position causing the closing of the switch 181, which thereupon energizes the solenoid 176 since, as indicated in Fig. 11, the contact buttons 185 and 186 are in contact when the bell crank lever 153 is in the drafting position. Upon energization of the solenoid 176, its armature 177 is drawn inward retracting the detent 173 from the notch 172 and permitting the rod 165 to move downward under the force of the spring 171. Owing to the longitudinal, vertical play permitted the pin 189 carrying the movable contact button 186, the electrical circuit between the contacts 185 and 186 is not broken until the rod 165 has moved downward sufficiently to assure the notch 172 being cleared by the pin 173 and assure that the spring 171 will move the rod 165 fully to the downward position.

In this manner the brake bar 157 is first brought in contact with the surface of the feed roll 32, stopping the rotation thereof, immediately thereafter drawing the feed roll 32 away from the driven feed roll 31 so that the supply strand 45 is no longer nipped and no further strand is fed through the drafting aprons 35 and 36. The opening of the contacts 185 and 186, as the rod 165 approaches its extreme downward position, serves to de-energize the solenoid 176 to avoid over-heating thereof, and to avoid closure of any electrical circuits while the apparatus is shut down.

Certain embodiments of the invention and certain methods of operation embraced therein have been shown and particularly described for the purpose of explaining the principle of operation of the invention and showing its application, but it will be obvious to those skilled in the art that many modifications and variations are possible, and it is intended therefore, to cover all such modifications and variations as fall within the scope of the invention which is defined in the appended claims.

What I claim is:

1. In the art of fabricating worsted yarn and the like, the process which comprises drawing a batch of fibers in the form of a strand in a drafting area of predetermined length greater than the length of substantially any of the fibers in the batch, drawing the fibers at the delivery end of the drafting area at a multiple of the surface

speed with which the fibers are fed to the entry end of the drafting area, applying lateral pressure to the fibers and confining them between confronting surfaces substantially throughout the length of the drafting area to maintain fiber control, and more closely confining the fibers toward the delivery end of the drafting area for increasing the magnitude of the lateral thrust by causing the confronting surfaces to converge from a spaced relationship to a substantially engaging relationship, whereby continuous fiber control is maintained without breaking the longest fibers or subjecting the strand to forces exceeding the elastic limit.

2. The art of fabricating worsted yarn or the like which comprises passing a batch of fibers in the form of a strand through drafting operations a predetermined number of times, in each of predetermined passages traveling the strand through a bed of faller points to a set of drafting rollers with a nip in close proximity to the faller point bed to control the fibers continuously throughout the length of the drafting area, and in another passage traveling the strand from feed rolls to front drafting rolls between opposed carrier aprons which extend from said feed rolls into close proximity with the nip of the front drafting rolls, causing said aprons to converge and applying gradually increasing lateral pressure to the strand while between said carrier aprons for gradually increasing resistance to movement of the strand to control the fibers continuously throughout the drafting area from feed rolls to draft rolls.

3. The art of fabricating yarn or the like which comprises passing a batch of fibers in the form of a strand through drafting operations a predetermined number of times, in at least one of said passages drawing the strand through a bed of faller points moving in the direction of longitudinal movement of the strand, nipping the strand in close proximity to the exit end of the bed of faller points and simultaneously laterally compressing the strand to a flat ribbon-like form, folding in the edges of the ribbon-like strand and in another of the passages drawing the strand from feed rolls to drafting rolls while retarding the strand between converging flexible surfaces subjecting the strand to progressively increasing lateral thrust to control the fibers continuously throughout the drafting area from the feed rolls to the drafting rolls while gradually increasing the resistance to movement of the strand.

4. The art of fabricating yarn or the like which comprises passing a batch of fibers in the form of a strand through drafting operations a predetermined number of times, in at least one of said passages drawing the strand through a bed of faller points moving in the direction of longitudinal movement of the strand, nipping the strand in close proximity to the exit end of the bed of faller points, folding in the edges of the ribbon-like strand and in another of the passages drawing the strand from feed rolls to drafting rolls while retarding the strand between converging flexible surfaces subjecting the strand to progressively increasing lateral thrust to control the fibers continuously throughout the drafting area from the feed rolls to the drafting rolls and increasing gradually the resistance to movement of the strand.

5. The art of fabricating worsted yarn or the like which comprises, blending different grades and qualities of fibers without regard for their staple lengths, passing a batch of the blend of

fibers in the form of a strand through drafting operations a predetermined number of times, including doublings in predetermined passages to blend the fibers uniformly longitudinally and transversely of the yarn, during each passage maintaining fiber control continuously throughout the length of the drafting area by lateral thrust, in the last passage progressively increasing such lateral thrust, thereby gradually increasing resistance to movement of the strand, and spinning the product strand of the last passage.

6. The art of fabricating worsted yarn or the like which comprises, passing a batch of a blend of wool fibers comprising the product strand of a combing machine through drafting operations a predetermined number of times, including fibers other than wool in the first passage following the combing machine, including doublings in predetermined passages to blend the various fibers uniformly longitudinally and transversely of the yarn, during each passage maintaining fiber control continuously throughout the length of the drafting area by lateral thrust, in the last passage progressively increasing such lateral thrust, thereby gradually increasing resistance to movement of the strand, and spinning the product strand of the last passage.

7. The method of attenuating a strand of fiber which comprises, travelling the strand longitudinally of itself in a drafting area from feed rolls along a path confined between surfaces into the nip of a set of front drafting rollers, the confining surfaces applying lateral thrust to the strand, causing the confining surfaces to approach each other more closely toward the delivery end and thereby progressively increasing the magnitude of lateral thrust applied by the opposed surfaces to the strand to increase gradually the resistance to movement thereof and maintaining such values of lateral thrust in successive portions of the drafting area as to produce retardation of the fibers of the strand to a predetermined extent.

8. The method of attenuating a strand of fiber which comprises confining the strand between confronting surfaces the surfaces traveling between a feed end and an exit end and being somewhat spaced at the feed end, causing said surfaces to travel in a serpentine path, the surfaces approaching each other more closely than at the feed end, applying progressively increasing lateral pressure to the strand of fiber and drawing said strand between said surfaces from feed rolls at a longitudinal speed exceeding the speed of said surfaces by nipping the strand closely beyond the exit end of said moving surfaces.

9. The method of attenuating a strand of fiber which comprises causing a pair of surfaces to travel in confronting relation along a path having a feed end and an exit end and reverse around a relatively small radius to permit coming into close proximity to the nip of drafting rolls, causing said surfaces to converge toward each other along the path of confronting relationship, for applying increasing lateral pressure to the strand, and drawing the strand of fibers through said surfaces from feed rolls while restraining the strand progressively during its passage between the surfaces and drawing it from the exit end with a close nip.

10. The method of attenuating a strand of fibers which comprises passing the strand longitudinally between a pair of spaced longitudinally moving surfaces, causing the surfaces to con-

verge continuously along the path of travel of the strand, thereafter bending the surfaces in a serpentine path to apply lateral thrust to the fibers, and drawing the strand between the surfaces in the same longitudinal direction as the direction of travel of the surfaces.

11. The method of attenuating a strand of fibers which comprises passing the strand longitudinally from feed rolls between a pair of spaced longitudinally moving surfaces, causing the surfaces to converge along an extended path for snubbing the strand and applying progressively increasing lateral thrust to the fibers for control thereof by causing the strand to follow a varying path, and drawing the strand between the surfaces in the same longitudinal direction as the direction of travel of the surfaces.

12. Apparatus for attenuating strands of fibers which comprises a pair of feed rolls, a pair of draft rolls and a pair of carrier aprons between said rolls extending substantially into the space bounded by the cylindrical surfaces of the draft rolls and an imaginary plane tangent to the draft rolls, said aprons having means for directing the aprons in serpentine paths in the portion of the aprons toward the draft rolls for snubbing the fibers, whereby continuous fiber control is maintained without subjecting the strand to forces exceeding the elastic limit, the confronting surfaces of the aprons near the feed rolls being spaced and converging in the direction toward the draft rolls.

13. Apparatus for attenuating strands of fibers which comprises a pair of feed rolls, a pair of draft rolls, a pair of carrier aprons between the said rolls extending in close proximity to the nip of the draft rolls, a pair of drive rolls supporting said carrier aprons at the end thereof toward said feed rolls, a pair of guide strips supporting the carrier aprons at the opposite end in close proximity to the nip of the draft rolls, snubber bars for directing the carrier aprons in a serpentine path along their confronting surfaces located between said drive rolls and said guide strips, said drive rolls having their axes so spaced as to provide spacing between the confronting surfaces of the carrier aprons in the area between said drive rolls and the nearest snubber bar, squeeze rolls mounted laterally movable adjacent said drive rolls, and means for resiliently pressing said squeeze rolls toward said drive rolls for holding said carrier aprons against the surfaces of their supporting drive rolls, whereby the carrier aprons are driven with a pushing action instead of a pulling action, normally stationary spindles on which said drive rolls are revolvably mounted, said spindles having eccentric square ends, side plates for supporting the apron assembly having straight-sided openings to receive the square ends of said spindles, whereby the lateral spacing between said drive rolls and accordingly the spacing between confronting surfaces of the carrier aprons at the entry end may be adjusted by adjusting the angular mounting position of the drive roll supporting spindles in said side plates, and means for rotatively driving said drive rolls.

14. Apparatus for attenuating strands of fibers which comprises a pair of feed rolls, a pair of draft rolls, a pair of carrier aprons between the said rolls extending in close proximity to the nip of the draft rolls, a pair of drive rolls supporting said carrier aprons at the end thereof toward said feed rolls, a pair of guide strips supporting the carrier aprons at the opposite end in close prox-

imity to the nip of the draft rolls, snubber bars for directing the carrier aprons in a serpentine path along their confronting surfaces located between said drive rolls and said guide strips, said drive rolls having their axes so spaced as to provide spacing between the confronting surfaces of the carrier aprons in the area between said drive rolls and the nearest snubber bar, squeeze rolls mounted laterally movable adjacent said drive rolls, and means for resiliently pressing said squeeze rolls toward said drive rolls for holding said carrier aprons against the surfaces of their supporting drive rolls, whereby the carrier aprons are driven with a pushing action instead of a pulling action.

15. Apparatus for attenuating strands of fibers which comprises a pair of feed rolls, a pair of draft rolls, a pair of carrier aprons between the said rolls extending in close proximity to the nip of the draft rolls, a pair of drive rolls supporting said carrier aprons at the end thereof toward said feed rolls, a pair of guide strips supporting the carrier aprons at the opposite end in close proximity to the nip of the draft rolls, and snubber bars for directly the carrier aprons in a serpentine path along their confronting surfaces located between said drive rolls and said guide strips, said drive rolls having their axes so spaced as to provide spacing between the confronting surfaces of the carrier aprons in the area between said drive rolls and the nearest snubber bar.

16. Apparatus for attenuating strands of fibers which comprises a pair of feed rolls, a pair of draft rolls, a pair of carrier aprons between the said rolls extending substantially into the space bounded by the cylindrical surfaces of the draft rolls and an imaginary plane tangent to the draft rolls, a pair of drive rolls supporting said carrier aprons at one end thereof toward said feed rolls, a pair of guide members supporting the carrier aprons at the opposite end, a pair of flat snubber bars each with an edge contacting one of said carrier aprons for directing the carrier aprons in a serpentine path along their confronting surfaces located between said drive rolls and said guide members, and means for rotating the drive rolls with greater surface speed than the feed rolls but less surface speed than the draft rolls whereby the drafting takes place between the feed rolls and the draft rolls and the carrier aprons serve to provide lateral fiber control without substantially drafting the fibers.

17. Apparatus for attenuating strands of fibers which comprises a pair of feed rolls, a pair of draft rolls, a pair of carrier aprons between the said rolls extending substantially into the space bounded by the cylindrical surfaces of the draft rolls and an imaginary plane tangent to the draft rolls, a pair of drive rolls supporting said carrier aprons at one end thereof, a pair of guide members supporting the carrier aprons at the opposite end, and auxiliary apron guide members located between said drive rolls and said end guide members, said drive rolls having their axes so spaced as to provide spacing between the confronting surfaces of the carrier aprons in the area between said drive rolls and the auxiliary guide members.

18. Apparatus for attenuating strands of fibers which comprises a pair of feed rolls, a pair of draft rolls, a pair of carrier aprons between the said rolls extending in close proximity to the nip of the draft rolls, a pair of drive rolls supporting said carrier aprons at the end thereof toward said feed rolls, a pair of guide strips supporting the carrier aprons at the opposite end in close

proximity to the nip of the draft rolls, said drive rolls having laterally movable axes to provide adjustability in the amount of spacing and pressure between confronting surfaces of the carrier aprons in the area adjacent the feed rolls, normally stationary spindles on which said drive rolls are removably mounted, said spindles having eccentric square ends, and side plates for supporting the apron assembly having straight-sided openings to receive the square ends of said spindles, whereby the lateral spacing between the confronting surfaces of the carrier aprons at the entry end may be adjusted by adjusting the angular mounting position of the drive roll supporting spindles in said side plates.

19. Apparatus for attenuating strands of fibers which comprises a pair of feed rolls, a pair of draft rolls, a pair of carrier aprons between the said rolls extending in close proximity to the nip of the draft rolls, a pair of drive rolls supporting said carrier aprons at the end thereof toward said feed rolls, a pair of guide strips supporting the carrier aprons at the opposite end in close proximity to the nip of the draft rolls, squeeze rolls mounted laterally movable adjacent said drive rolls, and means for resiliently pressing said squeeze rolls toward said drive rolls for holding said carrier aprons against the surfaces of their supporting drive rolls, whereby the carrier aprons are driven with a pushing action instead of a pulling action, said drive rolls being adapted to be rotatively driven.

20. An apron type drafting control apparatus for strands of fibers, comprising an apron drive shaft, a removable apron support comprising side plates, and a twin apron unit comprising two pairs of carrier aprons with guide strips for supporting lower ends of the aprons secured in slots in said side plates, drive rolls having normally stationary supporting spindles with eccentric square ends, said side plates having straight-sided slots for receiving said eccentric spindle ends in an angular position serving to provide desired spacing between drive rolls, common gearing rotatably inter-connecting said drive rolls and the said apron driving shaft, and squeeze rolls mounted in said side plates laterally movable with means for resiliently holding said squeeze rolls against the carrier aprons and in turn holding the carrier aprons against the drive roll surfaces for causing the drive rolls to drive the carrier aprons with a pushing action instead of a pulling action around said guide strips.

21. An apron type drafting control apparatus for strands of fibers, comprising an apron drive shaft, a removable apron support comprising side plates, and a twin apron unit comprising two pairs of carrier aprons with guide strips for supporting lower ends of the aprons secured in slots in said side plates, drive rolls, common gearing rotatably inter-connecting said drive rolls, and the said apron driving shaft, and squeeze rolls mounted in said side plates laterally movable with means for resiliently holding said squeeze rolls against the carrier aprons and in turn holding the carrier aprons against the drive roll surfaces for causing the drive rolls to drive the carrier aprons with a pushing action instead of a pulling action around said guide strips.

22. An apron type drafting control apparatus for strands of fibers, comprising an apron drive shaft, a removable apron support comprising side plates, and a twin apron unit comprising two pairs of carrier aprons with guide strips for supporting lower ends of the aprons secured in slots

in said side plates, drive rolls having normally stationary supporting spindles with eccentric square ends, said side plates having straight-sided slots for receiving said eccentric spindle ends in an angular position serving to provide desired spacing between drive rolls, and common gearing rotatably inter-connecting said drive rolls and the said apron driving shaft.

23. An apron type drafting control apparatus for strands of fibers, comprising two pairs of carrier aprons with guide strips for supporting lower ends of the aprons, drive rolls having normally stationary supporting spindles with eccentric square ends, side plates having straight-sided slots for receiving said eccentric spindle ends in an angular position serving to provide desired spacing between drive rolls, and squeeze rolls mounted in said side plates laterally movable with means for resiliently holding said squeeze rolls against the carrier aprons and in turn holding the carrier aprons against the drive roll surfaces for causing the drive rolls to drive the carrier aprons with a pushing action instead of a pulling action around said guide strips.

24. Apparatus for attenuating strands of fibers which comprises a pair of feed rolls between which fibers enter, a pair of draft rolls between which fibers are delivered, and carrier aprons between said pairs of rolls extending into close proximity to the nip of the draft rolls, said aprons comprising flexible surfaces spaced at the entry end and converging toward the delivery end, whereby continuous fiber control is maintained without breaking the longest fibers or subjecting

the strand to forces exceeding the elastic limit.

WILFRED J. CABANA.
